UNITED STATES PATENT OFFICE.

ANDREW S. PHELPS, OF CHICAGO, ILLINOIS.

HEATING-STOVE.

SPECIFICATION forming part of Letters Patent No. 400,481, dated April 2, 1889.

Application filed July 23, 1888. Serial No. 280,704. (No model.)

To all whom it may concern:

Be it known that I, ANDREW S. PHELPS, a citizen of the United States of America, residing at Chicago, in the county of Cook and State of Illinois, have invented certain new and useful Improvements in Heating-Stoves, of which the following is a specification, reference being had therein to the accompanying drawings, and the letters and figures of reference thereon, forming a part of this specification, in which—

Figure 1 is a side elevation of the stove. Fig. 2 is a central vertical elevation of the stove. Fig. 3 is a horizontal cross-sectional view, taken on line 3 of Fig. 1, looking down. Fig. 4 is a horizontal cross-sectional view, taken on line 2 of Fig. 1, looking down. Fig. 5 is a perspective view of the fingered plate for protecting the lower side of the opening in the dome leading to the downflue. Fig. 6 is a cross-sectional view of said plate; and Fig. 7 is a top plan view of the dome of the stove, showing the damper covering the opening in its upper part leading to the exit-flue.

Referring to the drawings, the fire-pot H, grate G, and base J are of the ordinary construction.

D is a cast-iron dome forming the combustion-chamber, the base of which dome rests in an annular channel in the ring R, resting on the top of the fire-pot; or, if desired, said annular chamber may be formed in the upper part of the fire-pot. Said channel is wide and deep enough to hold an accumulation of ash to prevent the escape of gas and smoke between the dome and fire-pot or the influx of air to injure combustion. Said dome is provided at the front part with a feed-opening 40 closed by a door, C, and an opening, O, at the back opposite the feed-opening leading to the downflue E, leading around the base J, and to the upflue F, which flues E and F are separated by the partition P', which turns to one side at its upper end and closes the upper end of flue E, as shown in Fig. 2. Said dome is so connected with the stove that it is free to contract and expand within its seat in ring R, and so arranged as to leave the

air-space g (shown in Fig. 4) between it and 50 the inner wall of upflue F, for the free circulation of air and protection to the parts adjacent to said air-space against too great heat. The said dome is also provided with an opening at the back in its upper part and above 55 the line of the upper part of the feed-door, which opening is provided with an ordinary damper, d, as shown in Figs. 2 and 7, and which opening leads to the direct upflue F, and is intended to be opened when the feed-door is open to prevent escape of gas when feeding the stove.

V is a fingered protecting-plate designed to rest loosely astride the bottom part of the opening O in the dome leading to the down- 65 flue, for the purpose of protecting the parts it covers from the heat and preventing fuel from falling over into said flue. This protecting-plate, by being loosely fitted in said opening, can be easily replaced when destroyed by 70 the heat.

B is an ornamental frame forming the outer case of the stove above the fire-pot and surrounding said dome, and is provided with small openings or perforations for permitting 75 radiation of heat from said dome.

Having thus described my invention, what I claim as new, and desire to secure by Letters Patent, is as follows, to wit—

In the stove shown and described, the conical-shaped dome D, forming the combustion-chamber and having a front feed opening or door, an opening leading to the indirect downflue E, opposite the feed-opening, and a direct-draft opening above said downflue-opening, leading to the upflue F and controlled by a damper, in combination with the perforated frame B, surrounding said dome, ring R, having the annular channel for dome D to rest in, fire-pot H, having a grate, downflue 85 E, and upflue F, arranged to leave the air-space g between it and said dome, substantially as and for the purpose set forth.

ANDREW S. PHELPS.
